UNITED STATES PATENT OFFICE.

BERTHOLD HOLZEL, OF NEW YORK, N. Y.

ATTACHMENT FOR FINGER-RINGS.

1,106,814.

Specification of Letters Patent. Patented Aug. 11, 1914.

Application filed August 25, 1913. Serial No. 736,559.

To all whom it may concern:

Be it known that I, BERTHOLD HOLZEL, a citizen of the United States, residing at 10 West Twenty-third street, in the city of New York, county and State of New York, have invented certain new and useful Improvements in Attachments for Finger-Rings, of which the following is a specification.

10 My invention relates to attachments for finger rings.

It provides a device of this character which enables a person to change a ring from a large finger and wear it on a smaller finger without discomfort or danger of losing the ring.

15 It further provides a device of this character which may be attached to the ring after the ring has been placed on the finger, and it serves to retain the ring in the proper position upon the finger.

20 My invention consists in the novel features of construction described herein, and illustrated in the drawings attached hereto and forming a part of this specification, and in which similar numerals of reference indicate corresponding parts.

25 Referring to the drawings: Figure 1 is an elevation view of a finger ring to which the device of my invention has been applied. Fig. 2 is a bottom plan view of my invention. Fig. 3 is a view similar to Fig. 2, but showing the pivoted clip member in a different position. Fig. 4 is an enlarged view 30 of the pivoted clip member.

35 My invention consists of a curved spring metal band —1— adapted to fit within a ring in the manner shown in Fig. 1. One end of the said spring metal band is formed with 40 the clip member —3— integral therewith, and having the lugs —4— and —5— adapted to engage the ordinary ring in a position illustrated. The other end of the said spring metal band carries the clip member 45 —2— pivoted thereto by means of a rivet or any other suitable fastening means. The clip member —2— carries the lugs —6— and —7— integral therewith and bent in substantially the same manner as the lugs 50 —4— and —5— of the clip member —3—, and disposed in the same relative position with respect to the spring metal band as the lugs of the clip member —3—. The said lugs —6— and —7— are also adapted 55 to engage the ring. The spring metal band is preferably formed with a curvature less

than that of the inside of the ring to which the device is to be applied. In manufacturing however the said spring band may be made with a curvature less than the 60 curvature of the inside of the largest ring carried in stock by the ordinary jeweler, thereby adapting the device to be used on any of the ordinary size rings without altering the curvature of the spring band. 65

In applying the device to the ring the spring clip members —2— and —3— are sprung onto the ring, the bottom surface of the said spring band lying adjacent the inside surface of the ring. The ring may 70 then be slipped over the finger in the usual manner. The resiliency of the spring band allowing it to pass over the knuckle of the finger, but holding the ring firmly in place against the finger. 75

The particular advantage in the device of my invention lies in the fact that the pivoted clip member —2— allows the device to be placed in position on the ring after the ring has been applied to the finger. In applying the device to the ring, after the ring is on the finger, the pivoted clip member —2— is turned to the position shown in Figs. 3 and 4 and sprung onto the inside of the ring. The spring metal band carrying the clip member —3— is then pushed in under the ring between the ring and finger and the clip member —3— sprung into place. It is evident that this last mentioned manner of applying the device to the ring 80 is particularly advantageous where the ring 85 is not large enough to allow the ring to slip over the knuckle with the device already inside. And herein lies the advantage of my device over the devices of this character 90 on the market at the present time, for most 95 of these devices must be applied to the ring before the ring is placed on the finger.

It is evident that modifications of the precise construction of my invention, as illustrated and described herein, may be made without departing from the spirit of my invention. 100

What I claim by Letters Patent of the United States of America is:

1. An attachment for finger rings comprising in combination, a spring metal band of less curvature than the ring and adapted to be positioned within the ring, a spring clip member disposed at one end of the said 105 band, a second spring clip member disposed at the opposite end of the band from said 110

first mentioned spring clip member and pivoted thereto, substantially as described.

2. An attachment for finger rings, comprising in combination, a spring metal band of less curvature than the ring and adapted to be positioned within the ring, a clip member disposed at one end of the said band and integral therewith, a second clip member disposed at the opposite end of the band

from said first mentioned clip member and pivoted thereto, substantially as described.

In testimony whereof I affix my signature in the presence of two witnesses.

BERTHOLD HOLZEL.

Witnesses:

RUDOLPH HANAN,
OTTO BUSECK.
